UNITED STATES PATENT OFFICE.

ISAAC H. GARSON, OF ROCHESTER, NEW YORK, ASSIGNOR, BY MESNE
ASSIGNMENT, TO MAMIE GARSON, OF SAME PLACE.

SUSPENDERS.

SPECIFICATION forming part of Letters Patent No. 244,581, dated July 19, 1881.

Application filed May 31, 1881. (No model.)

To all whom it may concern:

Be it known that I, ISAAC H. GARSON, of Rochester, Monroe county, New York, have invented a certain new and useful Improvement 5 in Suspenders; and I do hereby declare that the following is a full, clear, and exact description of the same, reference being had to the accompanying drawings, in which—

Figure 1 is a rear elevation of a pair of suspenders showing my improvement. Fig. 2 is a detail view.

My improvement relates to suspenders in which attachments are used for supporting the shirt-sleeves; and the invention consists 15 of suspenders having a single strap in the rear, which carries the junction of the shoulder-straps to the top of the shoulders, in combination with elastic ends attached to the shoulder-straps near the top, standing angularly 20 in line with the arms of the wearer, and provided with clasps which catch and hold upon the inner sides of the shirt-sleeves, as herein-after more fully described.

In the drawings, A A represent the two 25 rear button ends, and B represents a single length of elastic, which extends upward high on the shoulders of the wearer, so that the junction of the two shoulder-straps C C comes nearly to the neck, as near as possible, to allow 30 the shoulder-straps to pass on opposite sides with freedom. The lower ends of the button-straps, and also the ends of the elastic web, are covered on opposite sides by leather pads a a, and are stitched through.

To the lower front ends of the shoulder-straps are attached the ordinary front button-straps, D D, which may pass over pulleys in the usual way.

E E are small elastic straps stitched or otherwise 40 attached to the shoulder-straps on top of and just in front of the shoulders of the wearer, standing angularly downward in line with the arms, and provided with clasps b b of any suitable kind, by which they may be 45 caught on the shirt-sleeves on the inner side next to the breast and hold the same.

All the parts of the suspenders are made of inelastic material, except the back-strap B and the sleeve-holding straps E E, which are 50 elastic.

By the use of the elastic ends E E, attached to the shoulder-straps above the arms, the shirt-sleeves can be caught and held up at any desired elevation, leaving the lower ends of the sleeves entirely free, and the coat can be worn 55 without any inconvenience, since the sleeve-straps come on the inner side and lie flat and close to the arms.

To render the device practical and effective, the single back-strap B, reaching high upon 60 the shoulders, is necessary, as by this means the junction between the back-strap and the shoulder-straps is but a short distance from the attachment of the sleeve-straps to the shoulder-straps, and the shoulder-straps are thus 65 prevented from spreading laterally over the shoulders under the stress of the sleeve-straps, which they would do if their junction with the back-strap was carried low in the back, as in common suspenders. In such case the drawing action of the sleeve-straps would constantly 70 pull the shoulder-straps down over the shoulders.

I am aware that suspenders have been provided in the rear with a short elastic connection 75 between the button-straps and the shoulder-straps; also, that extra button ends have been used to support the drawers; such I do not claim.

What I claim as new, and desire to secure 80 by Letters Patent, is—

1. As an improvement in suspenders, the combination of the elastic back portion, B, arranged substantially as shown, with the sleeve-straps E E branching from the shoulder-straps 85 and adapted to be attached to and hold the shirt-sleeves in place, all as set forth.

2. As an improvement in suspenders, the elastic sleeve-straps attached to the shoulder-straps, as set forth, and extending on a line 90 of the arms when worn, and provided with attaching-clasps for holding the shirt-sleeves, all substantially as shown and described.

In witness whereof I have hereunto signed my name in the presence of two subscribing 95 witnesses.

ISAAC H. GARSON.

Witnesses:

R. F. OSGOOD,
R. E. WHITE.
